UNITED STATES PATENT OFFICE.

CHARLES S. SHALLENBERGER, OF ST. LOUIS, MISSOURI, ASSIGNOR TO SCULLIN-GALLAGHER IRON & STEEL COMPANY, OF ST. LOUIS, MISSOURI, A CORPORATION OF MISSOURI.

CAR-TRUCK.

No. 922,967.

Specification of Letters Patent.

Patented May 25, 1909.

Application filed June 5, 1908. Serial No. 436,873.

To all whom it may concern:

Be it known that I, CHARLES S. SHALLENBERGER, a citizen of the United States, residing at St. Louis, Missouri, have invented a certain new and useful Improvement in Car-Trucks, of which the following is a full, clear, and exact description, such as will enable others skilled in the art to which it appertains to make and use the same, reference being had to the accompanying drawings, forming part of this specification, in which—

Figure 1 is a side elevational view of a portion of a car truck constructed in accordance with my invention; and Fig. 2 is a top plan view thereof.

This invention relates to a new and useful improvement in car trucks.

A car truck of the type shown and described is provided with side frames having bolster-receiving openings and columns which form the sides of said openings, the bolster being slidingly mounted between said columns. In a truck of this type the shocks caused by stopping and starting the car cause the bolster to strike very severe hammer blows on the upper portion of the columns, and these hammer blows very often break or crack said columns.

In accordance with my invention the upper portion of each column is provided with a pair of ribs on its inner face which strengthen the upper portion of the columns and serve as guides for the bolster.

Referring to the drawings, A indicates truck side frames, each of which is preferably in the form of a single casting provided with a bolster-receiving opening 1. The sides of the opening 1 are formed by columns 2, the upper portion of each column 2 being provided with a pair of ribs 3 on its inner face. The inner faces of the columns and the ribs 3 form channel-shaped guideways and the bolster B is provided with lugs 4 which are arranged in said guide-ways. Springs 5 are interposed between the bolster and spring seats 6.

To remove the bolster from the truck the first step is to remove the springs 5 and allow the bolster to drop onto the spring seats 6.

When the bolster is resting on the spring seats its guide lugs are out of alignment with the ribs 3 and it can be moved longitudinally through the openings in the side frames.

I do not deem it necessary to show or describe the wheels, journal boxes and the various tie bars which are usually employed on a car truck as these elements form no part of this invention.

Having thus described the invention, what is claimed as new and desired to be secured by Letters Patent is:

1. In a car truck, side frames each having a bolster-receiving opening, columns forming the sides of said opening, the upper portion of each of said columns being provided with a pair of ribs, a bolster mounted between said columns and having guide lugs each of which projects into the space between a pair of said ribs, spring seats, and springs interposed between said bolster and spring seats; substantially as described.

2. In a car truck, side frames in the form of castings each having an opening, columns forming the sides of said opening, the upper portion only of each of said columns being provided with a pair of ribs on its inner face, a bolster having guide lugs, each of which projects into the space between a pair of said ribs and cooperates with the inner faces of said columns, spring seats, and springs interposed between said bolster and spring seats; substantially as described.

3. A side frame for car trucks in the form of a casting having a bolster-receiving opening, columns forming the sides of said opening, the upper portion only of each of said columns being provided with a pair of ribs which are formed integral with the columns and spaced apart so as to form a channel-shaped guideway for a bolster; substantially as described.

In testimony whereof I hereunto affix my signature in the presence of two witnesses, this first day of June 1908.

CHARLES S. SHALLENBERGER.
